CONTROL MECHANISM FOR HYDRAULIC PUMPS

Walter Ernst, Mount Gilead, Ohio, assignor to
 The Hydraulic Development Corp. Inc., Wil-
 mington, Del., a corporation of Delaware

Application December 26, 1942, Serial No. 470,136

6 Claims. (Cl. 103—38)

The present invention relates to hydraulic machinery and in particular to control devices therefor.

It is customary in the control of hydraulic pumps to employ a pivoted lever for operating the shift ring of the pump either directly, or indirectly through a servomotor. One end of the lever is usually connected to an electromagnet or a hydraulic thruster. The other end terminates in a knob which is adapted to be struck by the push rod of the platen when the latter is returning to its initial position. The linkage rods for actuating the shift ring and which are under the control of the electromagnet or thruster are connected between the pivoted lever and the control element of the hydraulic pump.

The pivoted lever and the linkage rods are usually keyed or otherwise secured together so that the movement of the lever is limited by the movement of the control linkage. At the beginning of the downward stroke, the lever is moved upwardly about its pivot away from the push rod. As the stroke proceeds the push rod moves downwardly with the platen and thus increases the distance between the lever and push rod. On the return stroke, the lever will reverse and back down, striking the push rod with a heavy impact which introduces jar into the various parts and may on occasion, fracture the lever.

The primary object of the invention is to provide improved structure by which the slamming effect between the lever knob and the push rod is avoided. This object is attained in brief by providing a yielding connection between the pivoted lever and the pump control linkage which will permit the rod on the lever to maintain a steady contact with the push rod even when the platen moves through a considerable distance. There can therefore be no sudden impact between the push rod and the pivoted lever when the platen is returning to its initial position.

The invention will be better understood when reference is made to the following specification and the accompanying drawing in which:

Figure 1 is a diagrammatic view of a variable delivery pump and an associated press together with the necessary levers and linkage for controlling the output of the pump to the press.

Figure 2 is a diagrammatic fragmentary view of the control lever and linkage shown at the left

of Figure 1 but in a different operating position.

Figure 3 is a plan view, somewhat enlarged, of the support on which the lever and certain parts of the linkage are mounted. This view is taken at the approximate position designated by the line 3—3 in Figure 1.

Figure 4 is a sectional view taken along line 4—4 in Figure 3.

Referring to the drawing, reference numeral 10 designates a variable delivery pump having a pair of oppositely extending casings 2, 3 one of which includes a reciprocating mechanism for reversing the hydraulic connections of the pump and the other casing contains a self-centering spring mechanism. The ingress and egress openings of the pump are brought out through a large casing 4 having ports 5, 6 which may constitute alternate inlet and discharge ports depending on the position of the valve controlling mechanism 15 within the casing 2. Conduits 7, 8 are taken respectively from opposite sides of the pump to a press cylinder 9, the upper end of which enters an oil reservoir 10. The cylinder contains a piston (not shown) having a piston rod 11 which extends downwardly from the cylinder and terminates in a platen 12. The conduits 7, 8 enter the cylinder 9 on opposite sides of the piston as is well known in the art. The reservoir tank 10 may include the usual form of surge valve and 20 other control devices, valves, etc., by which fluid is introduced into either end of the cylinder 9 and withdrawn from the opposite end as is well known in the art.

A rod or bar 13 is taken from the platen 12 and is provided at the end with an opening for slidably receiving a push rod 14. The latter is mounted in a guideway 15 and is provided at the upper end with a hardened shoulder portion 16. A slideable collar 17 is carried by the rod 14, and 25 is adapted to be fixedly secured to the rod by a screw 18.

A system of levers and linkage generally indicated at 19 is provided for controlling the mechanism within the casing 2. The mechanism 19 may comprise a lever 20 which is pivoted at its middle 21 on a support 22. The right hand end of the lever is swivelly connected to a rod 23 and a lever 24 which carries a control rod 25 reciprocably mounted in the casing 2. A pivoted link 26 is connected between the lever 24 and the

casing. The rod 25 is connected either with a servo-valve within the casing 2 or directly to a shift ring which controls the direction of movement of the pressure fluid delivered by the pump 1.

The left hand end of the lever 20 is swivelly connected to a downwardly depending rod 27 which carries a plunger 28 forming the actuated element of an electromagnetic device or thruster 29. A tension spring 30 may be connected between the left hand end of the lever 20 and a support 31. The arrangement is such that when the plunger 28 is caused to move downwardly the rod 23 moves upwardly to cause the rod 25 to shift to the right and to place the pump 1 on stroke. On the other hand, when the device 29 is de-energized or rendered inoperative the spring 30 will cause the lever 20 to move clockwise, thereby withdrawing the rod 25. The shift ring of the pump is thereby caused to move through neutral to its other extreme on-stroke position which in effect reverses the pump.

The pivot 21 may comprise a stub shaft as seen in Figure 3 which is secured to a support 32. In addition to the lever 20, the shaft 21 carries a lever 33 of which only the left hand end is pivoted on the shaft. The right hand end of the lever 33 terminates in a hardened steel knob 34 which normally rests on the collar 16. The lever 33 is provided with a circular hub 35 which serves to space the lever from the wall or support 32. At a position remote from the hub 35, the lever is provided with a pair of oppositely disposed segmental portions 36 of circular configuration and spaced from one another. These portions extend toward the lever 20. The latter is also provided with similarly shaped segments 38 which extend toward the lever 33. These segments 38 mesh with the segments 36 of the lever 33. In order to permit this meshing effect, suitable counterbored recesses are provided in the hubs of the respective levers as can be seen in Figure 3. The segments 38 have an inner periphery which loosely fits about the shaft 21 and are also provided with flat end surfaces. The width of the segments 38 is considerably less than the space on each side of the segments 36 so that in their meshing relation there is a wedge shaped space 39 between the two pairs of adjacent segments.

The levers 20, 33 are maintained in their proper position along the shaft 21 by means of a nut or screw collar 40 and if desired a washer 41 may be inserted between the collar and the outer surface 20.

Operation of the mechanism

Assume that the device 29 has been energized or actuated, the lever 20 will be caused to rotate counterclockwise carrying with it the segments 38. The latter turn on the shaft 21 to partially close the spaces 39. The rod 23 is given an upward movement and the control rod 25 is caused to move to the right, to place the pump on stroke. Pressure fluid is supplied by the pump to conduit 7 and withdrawn from the conduit 8, forcing the piston in the cylinder 9 to move downwardly and to carry the platen in the same direction. As the platen moves downwardly, the bar 13 also moves through the same distance permitting the push rod 14 to descend. It has been pointed out that the spaces 39 were not completely closed by the rotation of the segments 38 so that a sufficient space is left for the segments 36 to rotate clockwise. Thus, as the

push rod moves downwardly the lever 33 is permitted to follow the movement of the push rod so that the knob 34 continues to make contact with the collar 16. This condition is shown in Figure 2.

At the end of the work stroke any suitable apparatus may be employed to de-energize the device 29, for example a tonnage valve (not shown) which responds to excess back pressure above the piston in the cylinder 9. This valve when operated may open an electrical circuit through a limit switch which in turn controls the electromagnetic device 29. When the latter is de-energized the spring 30 immediately draws the plunger 28 upwardly causing the lever 20 to rotate clockwise and to withdraw the control rod 25 from the casing 2. Thus the shift ring in the pump 1 is moved through its neutral position to its other extreme on-stroke position whereby the pump discharge is reversed. Pressure fluid is now admitted to the conduit 8 and withdrawn from the conduit 7 to force the piston in the cylinder 9 upwardly.

It is apparent that when the lever 33 was moved clockwise during the downward motion of the platen the spaces 39 between the adjacent segments 36, 38 were moved from the position shown in Figure 4 to the position indicated at 42. Consequently, when the lever 20 is caused to move clockwise upon de-energization of the device 29 there is sufficient space at the positions 42 to accommodate a clockwise movement of the segments 36. During the return stroke of the platen the bar 13 moves upwardly and when the bar reaches the adjustable collar 17 the push rod is moved in a vertical direction, causing the lever 33 to move counterclockwise to its initial position.

During this movement the left hand face of the upper segment 36 (Figure 4) and the right hand face of the lower segment 38 are maintained in contact with the adjacent surfaces of the segments 38 so that an upward movement of the lever 33 causes the segments 38 to be rotated counterclockwise which in effect causes the lever 20 to be moved from the reverse on-stroke position to a horizontal neutral position. The rod 25 is therefore moved inwardly of the casing 2 to a position intermediate of its forward and reverse on-stroke positions and the shift ring is brought to its neutral position. Under these circumstances the output of the pump 1 is effectively cut off so that the piston in the cylinder 9 comes to rest at its uppermost position and poised ready to be driven downwardly when the device 29 is again actuated in any suitable and well known manner.

It is apparent that regardless of the instantaneous position of the push rod 14, the lever 33 maintains a continuous contact with the rod and there is no slamming effect between the collar 16 and the knob 34. Prior to the present invention, the levers 33 and 20 were keyed to the shaft 21 so that a counter-clockwise movement of the lever 20 would normally draw the knob 34 upwardly away from the collar and the distance would be increased as the push rod moves downwardly during the work stroke. When the platen was ready to return and the lever 20 was rotated clockwise, the lever 33 would normally back down and strike the collar 34. All of this tended to subject the parts including the shaft 21, linkages 23, 24 and the control rod 25 as well as the levers 20 and 33 to extreme jar and shock which on occasion might be sufficient to break one or

more of these parts depending on the distance that the platen had moved and the speed with which it was retracted.

However, by providing a yielding clutch or jaw mechanism obtained through the segments 36, 38 which permits the lever 33 to move clockwise when the lever 20 has been moved counterclockwise (Figure 2) the lever 33 is enabled to maintain a continuous contact with the push rod 14 and regardless of the position of the lever 20 so as to eliminate any impact of slamming proportions with the push rod. It is apparent that the width of the segments 36, 38 may be predetermined to provide the spacings 39 of proper width so as to permit the lever 20 to be rotated counter-clockwise and the lever 33 to be rotated clockwise and assume the respective positions shown in Figure 2. It is further evident that the presence of the spacings 39, when positioned as shown in Figure 4 or when the spacings have been effectively moved to the positions 42 cannot prevent the lever 33 from restoring the lever 20 to its horizontal or neutral position because at this time, the segments 36 are already in contact with the segments 38 and a counter-clockwise movement of segments 36 will obviously rotate the segments 38 through a corresponding angle in the counter-clockwise direction.

While I have described the invention on the assumption that the device 29 is of electro-magnetic type, this device may be constituted of a fluid pressure servomotor operator or other form of hydraulic thruster which may be controlled to initiate the operation and cause reversal of the pump discharge in any suitable and well known manner. Moreover, if desired the spring 30 may be contained within the casing 2 and the control rod 25 may constitute the valve stem of a hydraulic servomotor together with a hydraulic pilot control system (not shown).

Having thus fully described my invention, what I claim as new and desire to secure by Letters Patent is:

1. Apparatus for controlling the operation of a pressure fluid pump, said apparatus including a pair of levers rotatably mounted on a shaft, one end of one of said levers being pivotally connected to an actuating element and the other end of said one lever being connected to the control rod of the pump, the second of said pair of levers being connected to the first of said pair of levers through a lost motion coupling which permits the second lever to move in a direction opposite to the direction in which the first lever is moved by said actuating element, said flexible coupling comprising a plurality of interengaging segments secured to the respective levers and arranged about the shaft, and means for resiliently maintaining the parts of said levers in contact with each other prior to and during their movement in one direction.

2. Apparatus for controlling the operation of a pressure fluid pump, said apparatus including a pair of levers rotatably mounted on a shaft, one end of one of said levers being pivotally connected to an actuating element and the other end of said lever being connected to the control rod of the pump, the second of said pair of levers being connected to the first of said pair of levers through a lost motion coupling which permits the second lever to move in a direction opposite to the direction in which the first lever is moved by said actuating element, said coupling including two pairs of oppositely disposed

segmental members, one pair of members being secured to the other of said levers, said members being arranged about said shaft and having a width such as to provide spaces between the two pairs of the segmental members whereby one lever is adapted to move through a limited distance with respect to the other lever, and means for resiliently maintaining the parts of said levers in contact with each other prior to and during their movement in one direction.

3. In apparatus for controlling the operation of a pressure fluid pump, a push rod for shifting the control element of the pump to its neutral position, a pair of levers mounted on a shaft, one of said levers serving to control the on-stroke positions of the pump and the other lever serving to control the neutral position of the pump, said levers being connected together through a lost motion coupling which permits said other lever to maintain a continuous contact with said push rod said coupling comprising interengaging segments on said levers at the position of said shaft, and means for resiliently maintaining the parts of said levers in contact with each other prior to and during their movement in one direction.

4. In a control for a reversible delivery pump having a control element shiftable from a first position effecting full pump delivery in one direction, through neutral, to a second position effecting full pump delivery in the opposite direction, a shaft, a first double arm lever pivoted upon said shaft, a linkage connecting one end of said lever to said element, resilient means acting on the second end of said lever to thereby move said element into said first position, a power device connected to said second end of the lever to move said element into said second position against the action of said resilient means, a push rod, a second lever pivoted on said shaft and having its end continuously in contact with said rod for actuation thereby, and a lost motion connection between said levers whereby said second lever operates said first lever only from first position to neutral on corresponding motion of said push rod.

5. In a control for a reversible delivery pump having a control element shiftable between a first position effecting full delivery in one direction of flow and a second position effecting full delivery in the other direction of flow, a first lever pivoted intermediate its ends, a linkage operatively connecting one end of said lever with said element for so shifting said element, resilient means connected to urge said lever and element into said first position, a power device operable on the other end of said lever to move said element into said second position against the action of said resilient means, a push rod, a second lever pivoted adjacent said first lever and having a portion in continuous engagement with said push rod to be actuated by movement thereof, and a lost motion connection between said levers for effecting motion of said first lever by said second lever, from first position to neutral only, on corresponding movement of said push rod.

6. In a control system for a reversible pump having a control element movable from a first position effecting full pump delivery in one direction of flow, through neutral, to a second position effecting full pump delivery in the opposite direction of flow, a pivoted two-armed lever having one end connected to operate said element and having pivoted positions correspond-

ing to the said positions of said element, means connected to the second end of said lever urging the same into said first position, a power device connected to the second end of said lever operable to move said lever and element into said second position against the action of said urging means, a push rod adapted to be actuated by a device driven by the delivery of said pump, a second lever pivoted coaxially with and

adjacent said first lever and in continuous contact with said push rod for pivoting thereby, and a lost motion connection between said levers, said connection comprising segments coaxially fixed to the respective levers and engageable only to move said first lever from said first position to neutral by said second lever, in response to actuation of said push rod.

WALTER ERNST.
